UNITED STATES PATENT OFFICE.

FRANK D. ALLEN, OF STONECLIFF, WEST VIRGINIA.

CHARGING-CAR.

SPECIFICATION forming part of Letters Patent No. 655,179, dated August 7, 1900.

Application filed May 9, 1900. Serial No. 16,087. (No model.)

To all whom it may concern:

Be it known that I, FRANK D. ALLEN, residing at Stonecliff, in the county of Fayette and State of West Virginia, have invented a 5 new and Improved Charging-Car, of which the following is a specification.

This invention is in the nature of improvements in charging-cars for coke-ovens; and it primarily has for its object to provide a car 10 of this character of a simple and economical construction which can be easily manipulated and which will effectively serve for its intended purposes.

Another and essential object of my invention is to provide an improved structure of 15 charging-car including a revolving hopper supported upon the truck in such manner as to permit discharging the coal on the other side of the car without turning the entire car 20 about, as is generally necessary in the ordinary types of charging-cars of this kind.

With these objects in view my invention consists in certain details of construction and 25 peculiar combination of parts, all of which will hereinafter be fully explained, and particularly pointed out in the appended claims, reference being had to the accompanying drawings, in which—

Figure 1 is a side elevation of my improved 30 charging-car. Fig. 2 is an end elevation, the hopper being shown set to discharge at one side in full lines and to discharge at the other side in dotted lines. Fig. 3 is a view of the truck, the hopper supporting the ring being 35 shown in position in dotted lines. Fig. 4 is a detail view of the central bearing or turn-post.

In the practical construction my improved 40 charging-car includes generally a truck A and a hopper B, rotatably mounted upon the truck, the special manner in which the said hopper is mounted upon and connects with the truck forming an essential feature of my invention.

45 The truck A comprises the wheeled axles 1, the longitudinally-extending beams 2, mounted thereon, and the transverse beams 3, held in the plane with the beams 2.

The trucks A in practice are propelled upon 50 the trackway in any suitable manner; but for readily bringing the same into proper po-

sition over the ovens I prefer to provide the same with hand-operated propelling means consisting of a drive-shaft 5, mounted in brackets 6, supported on the cross-frame 6^a, 55 formed, preferably, of metal and made fast between the forward ends of the beams 2, as clearly shown in Fig. 3, by reference to which it will be noticed the said frame 6^a has a pair of standards 6^b, that straddle a fly-wheel 7, mounted upon the shaft 5, said standards 6^b also having bearings at their upper end for the double crank-shaft 8, which shaft carries a chain-wheel 8^a, geared by the chain-belt 9 with a double chain-wheel 5^a, mounted 65 on the shaft 5, which wheel 5^a receives motion from the chain 10, that connects it with a chain-wheel 11 upon the front axle of the truck, as shown. By providing the truck with a drive mechanism as described the operator or operators mounted on the truck can readily propel the same forward or backward, 70 as desired.

The truck-frame A also includes in my invention a pair of cross-beams 12, that extend 75 diagonally from one cross-beam 3 to the other, as clearly shown in Fig. 3, the ends of the said beams 12 being suitably braced by angle-plates 12^a. Mounted upon and made fast to the crossing portions of the beams 12 is a casting 13, having a central vertically-extending hub 13^a and an upwardly-projecting stud or spindle 13^b.

14, 14^a indicate guide-brackets mounted upon the beams 12, each having a tread or bearing-shoe portion 14^a and an overhanging guide-pulley 14^b, the purpose of which will herein-after appear.

B designates the hopper, which in my form of car has its bottom inclined transversely 90 from one side to the other, its lower or discharging mouth projecting to one side of the car-truck and having connected therewith a chute member 16, and while I have not illustrated it said mouth may also be equipped 95 with a gate or cut-off of any approved construction. The mouth and the chute portions are so projected and held relatively to the truck that they will clear all parts thereof when the hopper is rotated upon its supports. 100 The hopper is centrally supported upon a metal bracket 17, secured to the bottom of

the hopper, and having a pendent hub portion 18, that fits over the spindle 13^b of the casting 13, its lower end resting upon the hub 13^a of the said casting 13, as clearly illustrated in Fig. 1. This central bearing for the hopper serves as a sectional turn-post and also takes up some of the weight of the hopper, the bulk of which, however, is transmitted to the truck by a series of combined braces and supporting-rod 19, having substantially the same length and each being secured at the upper end to the upper member of the hopper and at the lower end to the casting or ring member 20, having an annular horizontal flange 20^a. This ring 20 is of such diameter that when fitted in a forward position the flange 20^a will seat upon the tread portions of the brackets 14 and ride under the guide-pulleys thereof. By this construction it is manifestly clear that the bulk of the weight of the hopper will be transmitted over a large area of the truck-frame and in such manner that the weight will be properly balanced to permit of a free turning around of the hopper.

25 A charging-car constructed in the manner shown and described provides for charging the ovens without the necessity of employing switch-outs or track-laterals, &c., to bring the truck about, as in my improvement the hopper can be readily turned to discharge at either side of the truck without turning the truck around.

I am aware that dumping-cars have heretofore been provided in which the hopper discharges to the side and in which the hopper has been rotatably supported upon the truck; but, so far as I know, the connections for joining hoppers of the kind stated with the truck have been more or less complex. My invention differentiates from what has heretofore been provided in this type of charging or dumping means in that the central bearing construction is simplified, and by reason of the manner in which the hopper is supported upon its annular ring the weight of the same is so balanced that the hopper can be readily turned around without any special releasing mechanism or adjustment of any of its parts.

45 Having thus described my invention, what

I claim, and desire to secure by Letters Pat- 50 ent, is—

1. In a dumping-car, the combination with a wheeled truck provided with a central turn-post; of a hopper having its outward end inclined to discharge to the side of the truck, 55 a hub pendently projected from the bottom of the hopper, said hub being rotatably mounted upon the turn-post, and means for bracing the hopper-body upon the car-truck, said means being rotatable with the hopper 60 as specified.

2. In a dumping-car, the combination with the wheeled truck, the central turn-post fixedly connected thereto, and a series of guide-flanges disposed in an annular arrangement 65 about the turn-post; of the hopper, said hopper having its bottom inclined and projected to discharge to the side of the truck; a pendent hub projected down from the bottom to fit upon the turn-post, a series of stay-rods 70 secured pendently to the hopper, and an annular flange supported from the lower end of the stay-rods, said flange engaging the fixedly-held annularly-disposed guides secured upon the truck substantially as shown and 75 for the purposes described.

3. In a dumping-car of the character described, the combination with the wheeled truck-frame, said frame including the crossed beams 12, and the guides 14, said guides having tread portions 14^a, the overhanging guide-rollers 14^c, and the casting 13 secured upon the beams 12, said casting having a hub 13^a, and the spindle 13^b; of the hopper, said hopper having its discharge-bottom inclined to 85 project from the side of the truck, the brackets 17 secured on the hopper-bottom said casting having an apertured hub 18, adapted to fit the spindle 13^b, the bars 19, and the ring 20, said ring having an annular flange 90 adapted to engage the guides 14, all being arranged substantially as shown and for the purposes described.

FRANK D. ALLEN.
